UNITED STATES PATENT OFFICE

2,436,310

SHUTTLE CHECK

Napoleon Lamarche, Lowell, Mass.

Application December 30, 1946, Serial No. 719,265

2 Claims. (Cl. 139—185)

1

The invention relates to shuttle checks for looms and more particularly to checks associated with shuttle boxes, as seen for example in Figs. 5 to 8 of the drawing of my United States Patent 2,305,534 of December 15, 1942. Each shuttle check must be pressed inwardly by a spring device, and the present invention aims to provide a simple inexpensive, effective and long-lived attachment whereby the required number of such spring devices may be mounted in operative relation with the check or checks.

Figure 1 of the accompanying drawings is a front elevation, partly broken away, showing the invention attached to a shuttle box and cooperating with the shuttle checks thereof.

Fig. 2 is a top plan view of the parts shown in Fig. 1.

Figs. 3, 4 and 5 are sectional views on the correspondingly numbered lines of Fig. 1.

Fig. 6 is a perspective view showing the major portion of the attachment.

A preferred construction has been illustrated and will be rather specifically described, with the understanding, however, that within the scope of the invention as claimed, variations may be made. The particular form of the invention disclosed cooperates with the four shuttle checks of the fur-cell shuttle box, but the invention may be constructed for coaction with any desired number of shuttle checks, even one.

In describing the invention, the terms "outer," "inner" and "inwardly" will be used to denote directions unidirectional with the lay, and "front," "rear," "forwardly" and "rearwardly" to denote directions at right angles to the lay.

A shuttle box 7 is shown having superposed cells 8 and appropriate shuttle checks 9 at the usual open front sides of said cells, said checks having forwardly offset outer ends provided with adjusting screws 19. At the outer end of the shuttle box 7, the horizontal webs 10 which form the tops and bottoms of the cells 8, are integrally joined to a vertical plate 11 in the usual way, this plate being mentioned simply because it is to this element of the shuttle box that the attachment is secured. As customarily manufactured, the plate 11 is formed near its outer edge with a vertical rib 12 and with horizontal ribs 13 projecting inwardly from said rib 12, and is formed at its inner edge with other horizontal ribs 14, all of said ribs being upon the front side of said plate 11. Regardless of this ribbed formation of the plate 11, the attachment of the present invention is so designed that it may be solidly fastened against the front side of said plate.

2

The attachment includes a vertically elongated attaching bar 15 for disposition at the front side of the plate 11 behind the forwardly offset ends of the checks 9, the rear side of said attaching bar 15 being formed with a longitudinal rib 16 for contact with the ribs 12 and 13, and being formed also with spaced vertical ribs 17 for contact with plate 11 between the ribs 14. The attaching bar 15 is solidly secured to the plate 11 by a number of cap screws 18. When the shuttle checks 9 are of the construction disclosed in the above mentioned patent, the adjusting screws 19 of said checks may well contact with the heads of the attaching screws 18, as shown.

Upper and lower horizontal arms 20 and 21 are integrally joined to the upper and lower ends of the attaching bar 15 and project beyond the inner edge thereof, said arms being located above and below the forwardly offset outer ends of the checks 9, respectively. Extending between the inner ends of these arms and integrally joined thereto, is a vertical bridge bar 22 which, when the attachment is fastened to the shuttle box, is forwardly spaced from the checks 9 and inwardly spaced from the forwardly offset outer ends of said checks 9. This bridge bar 22 carries a plurality of sockets 23 which, when the attachment is applied, open rearwardly toward the checks 9. The sockets 23 contain coiled compression springs 24 which exert rearward pressure on the checks 9, and said sockets are provided with suitable adjusting devices 25 for varying the strengths of said springs, thereby causing said checks to exert the necessary frictional braking force upon the shuttles.

From the foregoing, taken in connection with the accompanying drawings, it will be seen that novel and advantageous provision has been made for carrying out the object of the invention, and while preferences have been disclosed, attention is again invited to the possibility of making variations within the scope of the invention as claimed.

I claim:

1. In combination with a shuttle box and a shuttle check at the front side thereof, said check having a forwardly offset outer end spaced in front of the outer end of said shuttle box; a vertical attaching bar spaced behind said forwardly offset outer end of said check, means securing said attaching bar against the front side of said shuttle box, an upper arm integral with the upper end of said attaching bar and disposed over said forwardly offset outer end of said check, a lower arm integral with the lower end of said at-

taching bar and disposed under said forwardly offset outer end of said check, said upper and lower arms extending inwardly from said attaching bar toward the inner end of said shuttle box, a vertical bridge bar extending between the inner ends of said upper and lower arms and integrally joined thereto, said bridge bar being inwardly spaced from said forwardly offset outer end of said check and being forwardly spaced from the adjacent portion of said check, said bridge bar having a rearwardly open socket in front of said check, a spring seated in said socket and abutting the front side of said check, and an adjusting device for said spring threaded through the front end of said socket.

2. In combination with a shuttle box having vertically spaced shuttle cells, and shuttle checks at the front sides of said cells, said checks having forwardly offset outer ends spaced in front of the outer end of said shuttle box; and adjusting screws threaded through said offset outer ends of said checks and projecting rearwardly therefrom; a vertical attaching bar spaced behind said forwardly offset outer ends of said checks and said adjusting screws thereof, vertically spaced fasteners securing said attaching bar to the front side of said shuttle box and having heads abutting the aforesaid adjusting screws, an upper arm integral with the upper end of said attaching bar

and disposed over said forwardly offset outer ends of said checks, a lower arm integral with the lower end of said attaching bar and disposed under said forwardly offset outer ends of said checks, 5 said upper and lower arms extending inwardly from said attaching bar toward the inner end of said shuttle box, a vertical bridge bar extending between the inner ends of said upper and lower arms and integrally joined thereto, said bridge 10 bar being inwardly spaced from said forwardly offset outer ends of said checks and being forwardly spaced from the adjacent portions of said checks, said bridge bar having rearwardly open sockets in front of said checks, springs seated 15 in said sockets and abutting the front sides of said checks, and adjusting devices for said springs threaded through the front ends of said sockets.

NAPOLEON LAMARCHE.
